UNITED STATES PATENT OFFICE.

HARRY T. BRODEN, OF BROOKLYN, ASSIGNOR TO THE STANDARD CUT GLASS COMPANY, OF NEW YORK, N. Y.

DESIGN FOR A GLASS VESSEL.

SPECIFICATION forming part of Design No. 24,697, dated September 24, 1895.

Application filed August 9, 1895. Serial No. 558,788. Term of patent 7 years.

To all whom it may concern:

Be it known that I, HARRY T. BRODEN, a citizen of the United States, residing at Brooklyn, in the county of Kings and State of New York, have invented and produced a new and original Design for the Ornamentation of Glass Vessels, of which the following is a specification, reference being had to the accompanying drawings, forming a part thereof, 10 in which—

Figure 1 is a plan view of a dish embodying the features of the design; and Fig. 2 is a section through the dish, taken substantially on the line 2 2 of Fig. 1.

15 The design is applicable to any kind of glassware, such as bowls, plates, jugs, and dishes.

The leading feature of the design consists in lune prisms crossing one another at different angles, forming in outline substantially a many-pointed star, a central polygonal panel, and the sides of the prisms being deflected toward each other at their ends, forming conical end panels, together with conical prisms 25 formed within the outer conical panels, cross-hatching and checkering between the prism walls of the outer panels and the corresponding walls of the conical prisms, a portion of

the panels formed by the aforesaid conical prisms being decorated with cross-lines, and 30 minute prisms arranged in conjunction with the cross-hatching and the checkering to present a Gothic fenestrated appearance.

The minor features of the design consist in a button formed in the polygonal panel, lines 35 tangentially projected from the button, sundry of the lines meeting to form a triangle, and the various lines crossing one another, while minute prismatic figures are circularly arranged back of the lines around the button, 40 finished off by angular prismatic figures, forming a prismatic rosette within the said panel. Each alternate outer panel of the main stellated figure is given the gothic fenestrated appearance above described, and the 45 intermediate panels are decorated with rosette figures, substantially the same as the central rosette.

I claim—

The design for the ornamentation of glass 50 vessels, substantially as herein shown and described.

HARRY T. BRODEN.
